UNITED STATES PATENT OFFICE.

AMOS F. DIXON, OF NEWARK, NEW JERSEY, ASSIGNOR, BY MESNE ASSIGNMENTS, TO
WESTERN ELECTRIC COMPANY, INCORPORATED, A CORPORATION OF NEW YORK.

SELECTING SYSTEM.

1,222,853.

Specification of Letters Patent. Patented Apr. 17, 1917.

Application filed September 11, 1915. Serial No. 50,176.

To all whom it may concern:

Be it known that I, AMOS FREDERICK DIXON, a citizen of the United States, residing at Newark, in the county of Essex and State of New Jersey, have invented certain new and useful Improvements in Selecting Systems, of which the following is a full, clear, concise, and exact description.

This invention relates to selecting systems, and finds a particularly ready application in printing telegraph systems, although obviously not limited exclusively to this field.

The invention belongs particularly to that class of selecting systems wherein the signal current impulses coöperate sequentially with a plurality of electromagnetically actuated devices, such as relays, and the elements of a selecting apparatus, whereby various combinations of such impulses produce characteristic results; and one of its principal objects is to reduce the number of electromagnetically actuated devices heretofore required in systems of this character.

Another object of the invention is to provide a simple and improved arrangement of the above type for performing the desired selecting operations at the remote end of a transmission line of such length or under such circumstances, that it is desirable to dispense with a no-current interval between impulses.

To the above ends, the invention, in accordance with its general characteristics, contemplates a series of interdependently and sequentially acting electromagnetically actuated devices, whose operations are dependent upon the corresponding signal current impulses, and which coöperate to successively associate the elements of a selecting apparatus with means responsive only to impulses of certain characteristics, whereby the signal impulses may variably affect the selecting apparatus.

The above and other objects of this invention will be fully set forth in the following description and claims, and will be more readily understood by reference to the accompanying drawings, wherein Figure 1 shows the circuit connections of one form

of the invention; Fig. 2 shows a modification thereof, and Fig. 3 is a diagrammatic representation of one combination of signal current impulses.

The signal current impulses for effecting the operation of the selecting system may be imparted to the transmission line L by any desired form of apparatus. The type of apparatus disclosed in the drawings comprises a circuit controller and distributor. The controller is composed of a plurality of pole changers 1, 2, 3, 4 and 5, whose operations may be regulated by any of the well-known manually actuated devices wherein the controlling keys are arranged in the form of an ordinary typewriter keyboard, or by suitable automatic apparatus controlled by a perforated paper tape or the like. The right-hand fixed contacts of pole changers 1, 3 and 5 are connected to the positive terminal of a grounded source of energy 7, while the right-hand fixed contacts of pole changers 2 and 4 are connected to the negative terminal of a grounded source of energy 8. The left-hand fixed contacts of the pole changers are associated with a pair of sources of energy 9 and 10 in such a way that those pole changers whose shiftable contacts are moved from the right-hand to the left-hand fixed contacts cause an increase in the voltage normally supplied by the corresponding sources 7 and 8; in Fig. 3 this increased voltage is shown in the second and third impulses. The movable contacts of pole changers 1 to 5 inclusive are connected to segments 11, 12, 13, 14 and 15 respectively of a suitable current distributor D while an additional segment 16 is permanently connected to the negative pole of source 8 for a purpose to be hereinafter explained. The brush carrying arm of the distributor is adapted to be driven by any well-known means to continuously or intermittently rotate in the direction of the arrow, so that segments 11 to 16 inclusive are successively connected to the conducting ring 17 to which the transmission line L is joined.

Associated with line L is a pair of electromagnets forming a part of the selecting

100

system. These electromagnets preferably comprise a polarized relay 19 and a neutral relay 20. The polarized relay 19 responds characteristically to current impulses of both polarities and of any voltage, that is a positive impulse moves its armature in one direction and a negative impulse moves its armature in the opposite direction. On the other hand, the neutral relay 20 pulls up its armature in response only to impulses having certain characteristics; in the embodiment shown, those impulses of either polarity whose voltages are increased.

Relays 19 and 20 coöperate with a plurality of electromagnetically actuated devices or relays 21, 22, 23, 24 and 25 in such a manner that the relays are successively actuated in the order of the receipt of the line current impulses. Relay 19 is provided with a pivoted armature 28 connected to a grounded source of energy 29, and adapted to coöperate with a pair of contacts 30 and 31. Contacts 30 and 31 are connected to a pair of branch circuits 32 and 33, respectively, conductor 32 being connected to an armature 34 of relay 21, and conductor 33 to an armature 35 of relay 22. Armature 34 co-operates with a front contact connected to an armature 36 of relay 23, this armature coöperating with a back contact connected to the winding of relay 22 and a front contact connected to an armature 37 of relay 25. Armature 35 of relay 22 co-operates with a back contact connected to the winding of relay 21 and with a front contact connected to an armature 38 of relay 24, which armature is associated with a back contact connected to the winding of relay 23 and a front contact connected to the winding of relay 25. Relays 21 to 25 inclusive are also provided with locking armatures 42, 43, 44 and 45, respectively, which are normally connected to a grounded source of energy 46, through the back contact, and an armature 47 of a clear-out relay 48. With this arrangement of connections, as will be presently explained, the passage of current impulses of opposite polarity through the polarized relay 19 causes the successive energization of relays 21 to 25. Relays 22, 23 and 24 are also provided with armatures 49, 50 and 51 respectively, each of which is associated with a back contact connected to an element or selecting mechanism 61, 62 and 63 of any desired form of selecting apparatus. Elements 64 and 65 of the selecting apparatus are respectively connected to back and front contacts associated with an armature 66 of relay 25. The front contact of armature 49 is connected to armature 50, the front contact of armature 50 is connected to armature 51, and the front contact of armature 51 is connected to armature 66. The selecting apparatus may be of any desired type; for example,

that disclosed in Patent No. 1,103,133, issued July 14, 1914, and the elements 61-65 thereof are controlled through the agency of an armature 68 of relay 20. Armature 68 is connected to a grounded source of energy 69 and associated with a front contact connected to armature 49 of relay 22. A front contact associated with armature 68 is connected to armature 49 by a conductor 70. From the foregoing, it will be apparent that the successive energization of relays 21 to 24 extends conductors 32 and 33 to effect the energization of the next relay in the series, and extends conductor 70 into connection with the next corresponding mechanism 61 to 65.

In operation, upon the receipt of the first impulse of any combination of signal impulses, polarized relay 19 moves its armature 28 from contact 30 to contact 31, and a circuit is completed from grounded source 29, armature 28, contact 31, conductor 33, armature 35 and relay 21 to ground. Relay 21 thereupon attracts its armatures 34 and 41, armature 41 completing a holding circuit from source 46 through armature 47. Armature 34 extends conductor 32 through armature 36 and its associated back contact to the winding of relay 22, which circuit, up to armature 36, is retained until the holding circuit of relay 21 is broken by the energization of clear-out relay 48. During the reversal in polarity between the first and second impulses, armature 28 moves from contact 31 back to contact 30, and a circuit is completed from grounded source 29 through armature 28, contact 30, conductor 32, armature 34 and its coöperating front contact, armature 36 and its coöperating back contact and relay 22 to ground, whereupon relay 22 attracts its armatures 35, 42 and 49. The attraction of armature 35 extends conductor 33 through armature 38 and its coöperating back contact to relay 23. Armature 42 completes a holding circuit for relay 22 from source 46, through armature 47, and armature 49 extends conductor 70 through armature 50 to mechanism 62. These operations continue during the receipt of the five impulses, the sixth impulse, through segment 16, acting merely to return armature 28 to its normal position in engagement with contact 30.

Whenever one of the impulses is of the necessary increased voltage, relay 20, in addition to relay 19, is energized, and grounded source 69 is connected to a corresponding selecting mechanism 61 to 65 inclusive through the corresponding armatures 49 to 51 and 66. In the combination of impulses disclosed in Fig. 3, mechanisms 62 and 63 only would be operated. The successive operation of the selecting mechanisms being completed, clear-out relay 48 is energized.

rechts verlängerte Auslastung von 1.222,85

by any suitable means, whereupon the holding circuits for relays 21 to 25 inclusive are broken and the apparatus returns to normal condition ready to receive a new combination of impulses.

The modification disclosed in Fig. 2 allows one of the electromagnetically actuated devices to be dispensed with, armature 28 of relay 19 being connected to a condenser 100 instead of a source of energy. The sequentially acting relays 101, 102, 103 and 104 of the modified arrangement are divided into two groups of two relays each, relays 101 and 103 forming one group and being energized upon the discharge of condenser 100, while relays 102 and 104, forming the second group, are energized upon the charging of condenser 100. One terminal of the windings of relays 101 and 103, therefore, is grounded, while the corresponding terminal of the windings of relays 102 and 104 is respectively connected to sources of energy 105 and 106. It is understood that the relays of each group are to be energized successively in the manner set forth in describing the system illustrated in Fig. 1. Relays 101 to 104 inclusive are each provided with a locking armature 107, which completes holding circuits through one of the back contacts and armatures 108 and 109 of clear-out relay 110. Armature 108 is grounded, while armature 109 is connected to a grounded source of energy 112. Relay 101 is provided with an armature 115 coöperating with a back contact connected to a grounded source of energy 116 and a front contact connected to an armature 117 of relay 103. Armature 117 coöperates with a back contact connected to relay 102, and a front contact connected to relay 104. Conductor 32 is extended through armature 120 and its back contact to relay 101 or through armature 120 and its front contact and armature 121 of relay 104 to relay 103. Armatures 130, 131, 132 and 133 of relays 101 to 104 inclusive coöperate with armature 68 of relay 20 to effect the energization of mechanisms 61 to 65 inclusive of the selecting apparatus.

In accordance with this arrangement, the first impulse causing armature 28 of relay 19 to engage contact 31 effects the charging of condenser 100 by source 116. If this impulse is of a higher voltage, relay 20 is also energized, causing source 69 to operate mechanism 61. The second impulse, returning armature 28 to contact 30, discharges condenser 100 through conductor 32, armature 120 and relay 101, to ground, which effects the energization of relay 101, and the actuation of armatures 115, 107 and 130. The actuation of armature 115 extends conductor 33 through armature 115 and front contact thereof, armature 117 and back contact

act thereof and winding of relay 102 to 65 grounded battery 105. The actuation of armature 107 establishes a holding circuit from grounded source 12, armature 109 of clear-out relay 110, armature 107 and winding of relay 101 to ground. The actuation 70 of armature 130 extends conductor 70 to selecting mechanism 62 by way of armature 130 and front contact thereof, armature 131 and back contact thereof and winding of mechanism 62 to ground. The next impulse 75 moving armature 28 against contact 31 causes the charging of condenser 100 from source 105 through relay 102, armatures 117 and 115 and conductor 33, relay 102 becoming energized and pulling up its armatures. 80 The fourth impulse effects the energization of relay 103 by the discharge of condenser 100, and the last selecting impulse effects the energization of relay 104. The sixth impulse merely restores armature 28 as before. 85 Any impulse of the combination which is of increased voltage effects the operation of the corresponding selecting mechanism 61 to 65 inclusive. When the selective action is completed, the energization of clear-out relay 90 110 by any desired means returns the entire apparatus to normal.

The invention claimed is:

1. A selecting system comprising a plurality of electromagnetically actuated devices, a plurality of selecting mechanisms, an electromagnet responsive to all current impulses received for effecting the successive operation of said devices in invariable order, and means responsive only to certain impulses and successively associated with said mechanisms by said devices for selectively affecting said mechanisms. 95 100

2. A selecting system comprising a plurality of relays, selecting mechanisms, an electromagnet characteristically responsive to signal current impulses of both polarities and coöperating with said relays to cause said relays to be successively operated, and a second electromagnet responsive only to current impulses with certain characteristics and adapted to be brought successively into operative relation with said mechanisms by said relays, whereby various combinations of current impulses variably affect said mechanisms.

3. A selecting system comprising a series of selecting mechanisms means characteristically responsive to current impulses of certain characteristics, and a series of relays adapted to operate in predetermined sequence and to successively associate said means with said mechanisms, the last relay of the series bringing the last two of said series of mechanisms into operative relation with said means. 120 125

4. A selecting system comprising a plurality of selecting mechanisms, means char-

acteristically responsive to current impulses of certain characteristics, a condenser, and a plurality of relays divided into groups, the relays of one group being energized by the charge of said condenser and those of another group being energized by the discharge thereof, said relays acting sequentially to

bring said mechanisms successively under the control of said means.

In witness whereof I hereunto subscribe to my name this 7th day of September, A. D. 1915.

AMOS F. DIXON.
